(57) CLAIM

The ornamental design for a tub with cabinet, as shown and described.

DESCRIPTION

FIG. 1 is a top front perspective view of a tub with cabinet showing my new design;

FIG. 2 is a left side perspective view, the right side being a mirror image thereof;

FIG. 3 is a front and left side perspective view, the right side being a mirror image thereof; and,

FIG. 4 is a top perspective showing the left side and back. The broken lines shown are for illustrative purposes only and form no part of the claimed design.
